Primary Examiner — Katrina A Betton*(74) Attorney, Agent, or Firm* — Seed IP Law Group PLLC(57) **CLAIM**

The ornamental design for a arm-binding connector of wiper for automobiles, as shown and described.

DESCRIPTION

FIG. 1 is a perspective view of the arm-binding connector of wiper for automobiles showing my new design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof; and,

FIG. 8 is an isometric view showing the arm-binding connector in a state of use with a wiper for automobiles, the wiper shown in broken lines.

The broken lines shown in FIG. 8 are for the purpose of illustrating the state of use of the article of this design and forms no part of the claimed design.
